UNITED STATES PATENT OFFICE

NELSON W. WEBB, OF BELLEVILLE, NEW JERSEY, ASSIGNOR TO EASTWOOD WIRE CORPORATION, OF BELLEVILLE, NEW JERSEY, A CORPORATION OF NEW JERSEY

WOVEN WIRE BELT FOR PAPER-MAKING MACHINES

Application filed August 29, 1930. Serial No. 478,622.

The present invention relates to woven wire belts, particularly for paper-making machines of the Fourdrinier type, and has for an object to provide an improved seam which 5 may be produced with facility, will be of great strength, and will closely approximate the structure of the body of the wire as to strength, flexibility, and porosity.

In Fourdrinier wires, the construction of 10 various mesh wires is practically standardized, and in any given mesh there is less space between the warp wires, where the lacing wire must lie, than the diameter of the warp wires, so that it has been the practice to 15 employ a lacing wire for the seam of smaller diameter than the warp wires to enable the operator producing the seam to thread it through the constricted mesh openings. The resultant seam, particularly if it is of the 20 skip-seam type, where the lacing wire is passed through every other mesh opening, is therefore of much less strength than the body of the cloth and in use upon the paper machine is apt to open up. It has also been 25 the practice to employ needles to facilitate threading of the lacing wire through the constricted mesh openings, and these would very often cut the warp ends and produce irregularities in the seam.

30 It is a particular object of the present invention to provide a seam structure in which the lacing wire may be of same or greater diameter than the warp wires, and to this end I propose to provide at the butted end of the 35 wires alternate mesh openings of greater width than the mesh openings throughout the body of the wire, and which are adapted to have the lacing wire readily threaded therethrough, without the use of needles, and with greater speed and uniformity than has heretofore obtained.

It is another object to provide a seam in 40 which the lacing wire will be more nearly parallel to the warp wires at the wear side than is the case with the usual skip-seam, so 45 that it will not be subjected to excessive wear and cutting through contact with the edges of the grooves that are usually cut in the suction boxes by the wire knuckles. It is further proposed to so arrange the warp wire ends as

to tend to widen and smooth any grooves in the suction boxes.

With the above and other objects in view an embodiment of the invention is shown in the accompanying drawing, and this embodiment will be hereinafter more fully described with reference thereto, and the invention will be finally pointed out in the claims.

In the drawing:

Fig. 1 is an enlarged plan view of a portion 60 of one side of the belt at the seam,

Fig. 2 is a sectional view taken along the line 2—2 of Fig. 1, and

Fig. 3 is a plan view of the other side from 65 that shown in Fig. 1.

Similar reference characters indicate corresponding parts throughout the several figures of the drawing.

Referring to the drawing, Fig. 1 shows, 70 greatly enlarged, a portion of the two ends of the wire cloth which are seamed together to form a belt, the portion, as shown, representing a piece of belt which in its actual size is about $\frac{1}{2}$ of an inch long, there being about 60 warp wires to the inch. The wire 75 cloth consists of warp wires 10 and weft wires 11 of brass, bronze or other suitable material for the purpose.

At each end of the cloth the warp wires disposed at one side of the end weft wire 80 (the under side as shown in Fig. 1) are arranged in slightly angular relation, as at 12, being inclined in one direction at one end and in the other direction at the other end, so that in the butted relation of the wire ends the 85 angular bent warp ends are substantially parallel. The alternate mesh openings 13 adjacent the end weft wires, due to this arrangement of the warp wire ends, are wider than the normal mesh openings in the body 90 of the cloth, and are adapted to have the lacing wire threaded therethrough as will hereinafter more fully appear.

In order to securely maintain this arrangement of the warp wire ends and at the same 95 time provide a firm anchor for the lacing wire the end weft wires are preferably of the type disclosed in my Patent No. 1,747,272, granted February 18, 1930, and which consists of a solder-coated wire 14 inserted between the 100

warp wire ends in substitution of a removed weft wire. The solder-coated wire is joined to the warp wire ends by the application of heat, which causes the solder to flow to the 5 warp wire ends to integrally join and truss them, and mesh openings between the wires being at the same time maintained uniformly free of lumpy spots, because of the capillary flow of the metal away from them.

10 The seam is now completed by sewing the lacing wire 15 about the two butted ends of the wire cloth, the same being passed through the relatively large alternately arranged mesh openings 13. The butted ends are preferably so disposed that the straight warp 15 ends at the upper side of the end weft wires, as shown in Fig. 1, are in line with each other, so that the lacing wire will be flat without having to pass over any knuckles.

20 The lacing wire, which may be of greater diameter than the normal mesh openings, may be sewed in with great facility and without the use of needles, so that a seam of great 25 strength and uniformity is produced with a great saving in time and with the elimination to a great extent of defective seams. In use upon the paper machine the lacing wire is not subject to as great wear as has been the case heretofore, because of the greater alignment with the warp knuckles, and also the 30 angularly disposed warp ends will tend to smooth the corners of grooves cut in the suction boxes, so that the wire will move over the suction boxes more smoothly, and cutting 35 of the groove edges across the lacing wires, which has heretofore resulted in excessive and rapid wear of the lacing wire, will be greatly reduced.

I have illustrated and described a preferred and satisfactory embodiment of the 40 invention, but it will be obvious that changes may be made therein, within the spirit and scope thereof, as defined in the appended claims.

45 Having thus described my invention, what I claim and desire to secure by Letters Patent is:—

1. In a wire cloth belt, a length of woven wire cloth comprising warp and weft wires 50 and having its ends adjacent, the warp and weft wires being spaced to provide mesh openings, certain mesh openings contiguous to the ends of the cloth being relatively wider than the other mesh openings disposed 55 in transverse alignment therewith, said certain mesh openings being bounded by the end weft wire, the next adjacent weft wire, a warp wire end overlying said end weft wire, and a warp wire end underlying said end weft wire, and a warp wire end 60 being disposed in divergent relation to the overlying warp wire end, means fixedly securing said warp wire ends to said end weft wire whereby said relatively wider mesh 65 openings are of predeterminedly fixed size

for having a lacing wire passed therethrough, and a lacing wire connecting the ends of the cloth and passed only through said relatively wider mesh openings and overlying said end weft wires at points contiguously opposed to said underlying warp wire ends. 70

2. In a wire cloth belt, a length of woven wire cloth comprising warp and weft wires and having its ends adjacent, the warp and weft wires being spaced to provide mesh openings, certain of the warp wire ends being at one side of the end weft wires, and the other warp wire ends being at the other side of said end weft wires, all of said warp wire ends at one side being angularly bent sidewise in the same direction, whereby certain mesh openings contiguous to the ends of the cloth are relatively wider than the other mesh openings disposed in transverse alignment therewith, said certain mesh openings being bounded by the end weft wire, the next adjacent weft wire, a warp wire end overlying said end weft wire, and a warp wire end underlying said end weft wire, means fixedly securing said warp wire ends to said end weft wire whereby said relatively wider mesh openings are of predeterminedly fixed size for having a lacing wire passed therethrough, and a lacing wire connecting the ends of the cloth and passed only through said relatively wider mesh openings and overlying said end weft wires at points contiguously opposed to said underlying warp wire ends. 80

3. In a wire cloth belt, a length of woven wire cloth comprising warp and weft wires and having its ends adjacent, the warp and weft wires being spaced to provide mesh openings, the warp wire ends being alternately at opposed sides of the end weft wires, all of said warp wire ends at one side being angularly bent sidewise in the same direction, whereby the alternate mesh openings contiguous to the ends of the cloth are relatively wider than the other mesh openings disposed in transverse alignment therewith, said alternate relatively wider mesh openings being bounded by the end weft wire, the next adjacent weft wire, a warp wire end overlying said end weft wire, and a warp wire end underlying said end weft wire, means fixedly securing said warp wire ends to said end weft wire whereby said relatively wider mesh openings are of predeterminedly fixed size for having a lacing wire passed therethrough, and a lacing wire connecting the ends of the cloth and passed only through said relatively wider mesh openings and overlying said end weft wires at points contiguously opposed to said underlying warp wire ends. 90

4. In a wire cloth belt, a length of woven wire cloth comprising warp and weft wires and having its ends adjacent, a replacement 100

- weft wire at each end engaged between the overlying and underlying warp wire ends in substitution of a removed and previously woven-in weft wire, the warp and weft wires being spaced to provide mesh openings, all of the warp wire ends at one side of said replacement weft strand being angularly bent sidewise in the same direction, whereby certain mesh openings contiguous to the ends of the cloth are relatively wider than the other mesh openings disposed in transverse alignment therewith, said certain mesh openings being bounded by said replacement end weft wire, the next adjacent weft wire, a warp wire end overlying said end weft wire, and a warp wire end underlying said end weft wire, means permanently fixing said warp wire ends to said end weft wire whereby said mesh openings are of predeterminedly fixed size
- for having a lacing wire passed therethrough, and a lacing wire connecting the ends of the cloth and passed only through said relatively wider mesh openings and overlying said end weft wires at points contiguously opposed to underlying warp wire ends.
5. In a wire cloth belt, a length of woven wire cloth comprising warp and weft wires and having its ends adjacent, the warp and weft wires being spaced to provide mesh openings, certain of the warp wire ends being at one side of the end weft wires, and the other warp wire ends being at the other side of said end weft wires, all of said warp wire ends at one side being angularly bent sidewise in the same direction, whereby certain mesh openings contiguous to the ends of the cloth are relatively wider than the other mesh openings disposed in transverse alignment therewith, said certain mesh openings being bounded by the end weft wire, the next adjacent weft wire, a warp wire end overlying said end weft wire, and a warp wire end underlying said end weft wire, said underlying warp wire end being disposed in divergent relation to the overlying warp wire end, means permanently fixing said warp wire ends to said end weft wire whereby said mesh openings are of predeterminedly fixed size for having a lacing wire passed therethrough, and a lacing wire connecting the ends of the cloth and passed only through said relatively wider mesh openings and overlying said end weft wires at points contiguously opposed to said underlying warp wire ends, the angularly bent warp ends at the adjacent ends of the cloth being at the under side of the belt and in parallel relation to each other, and the warp wires having said bent ends being longitudinally aligned at each side of the connected ends.

Signed at Belleville, county of Essex, and State of New Jersey, this 15th day of January, 1930.

NELSON W. WEBB.
